UNITED STATES PATENT OFFICE.

NATHAN E. NASH, OF TORONTO, CANADA.

TEMPERATURE-REGULATOR.

SPECIFICATION forming part of Letters Patent No. 733,329, dated July 7, 1903.

Application filed June 17, 1901. Serial No. 64,949. (No model.)

To all whom it may concern:

Be it known that I, NATHAN E. NASH, a citizen of the United States of America, and a resident of the city of Toronto, in the county 5 of York, Province of Ontario, and Dominion of Canada, have invented certain new and useful Improvements in Regulating-Valves; and I hereby declare that the following is a full, clear, and exact description of the same.

10 This invention relates to certain new and useful improvements in that class of temperature-regulating appliances in which is employed a pressure-operated valve apparatus; and it relates more particularly to the peculiar construction and operation of a regulating-valve for controlling the flow of the pressure fluid to the pressure-operated valve to apply the closing motion thereto; and the object of the invention is to construct a regulating-valve highly susceptible to any variation of temperature and acutely affected thereby and capable of responding easily and quickly when so affected to allow of the flow of the pressure fluid to the pressure-operated 25 valve, to apply the closing motion thereto when the temperature has risen above a predetermined degree, or to cut off the flow of the pressure fluid when the temperature has fallen below the same degree and relieve the 30 pressure-operated valve of such closing pressure.

A further object of the invention is to so construct the regulating-valve as to minimize the friction of the moving parts and to so arrange 35 the motor-valve that it will be retained on its seat regardless of the fluid-pressure within the regulating-valve when normally checking the flow of the pressure fluid to the pressure-operated valve, as hereinafter more 40 fully set forth, and more particularly pointed out in the claims.

I do not confine the use of the regulating-valve to any specific purposes, although for explanatory purposes I have shown it used in 45 connection with a radiator.

In the drawings, Figure 1 is a perspective view of the exterior of the regulating-valve. Fig. 2 is a view showing the regulating-valve interposed on the pressure-fluid pipe between 50 the reservoir and the pressure-operated valve, the pressure-operated valve being shown in section and connected to a radiator. Fig. 3

is a vertical section through the regulating-valve, showing the motor-valve in position to allow of the flow of the pressure fluid to the 55 pressure-operated valve. Fig. 4 is a sectional view taken at right angles to Fig. 3, showing the motor-valve in the same position as in Fig. 3. Fig. 5 is a sectional view corresponding to Fig. 3, showing the motor-valve in position to arrest the flow of the pressure fluid. Fig. 6 is a sectional view of the throttle-valve for cutting off the flow of the pressure fluid through the regulating-valve.

Like letters of reference refer to like parts 65 throughout the specification and drawings.

a represents the valve body or casing, in which is formed a motor-chamber *b*, having its inner end closed by a valve-seat *b'* and its outer end by a removable plug *c*. Entering 70 the motor-chamber *b* contiguous to the valve-seat *b'* is the inlet-channel *d*, through which the operating fluid is admitted to the motor-chamber, and formed in the motor-chamber *b* between the inlet-channel *d* and its outer 75 end is an enlargement or valve-chamber *e*, the inner edge of which is fitted with a valve-seat *f*. That part of the motor-chamber *b* between the valve-seat *f* and the outer end is of a slightly-greater diameter than that part 80 between the seat *f* and the inner end of the motor-chamber, as shown in Figs. 3, 4, and 5 of the drawings.

Contained within the motor-chamber *b* is a motor-valve *g* of varying diameters corresponding to the varying diameters of the motor-chamber and fitted with a beveled shoulder forming subsidiary valve *h* to engage the valve-seat *f*. The inner end of the motor-valve *g* is fitted with a valve-stem *i*, operating 85 through a correspondingly-shaped hole *j*, formed through the valve-casing *a* and valve-seat *b'*.

Formed in the valve-casing *a* is an outlet-channel *k*, communicating with the valve-chamber *e* and with the outlet-port *d'* and also with an auxiliary outlet-port *l*, formed in the valve-casing, the outlet-channel being of substantially the same width as the valve-stem *i* and at a substantially right angle thereto. That portion of the valve-stem *i* contained in the outlet-channel *k* when the valve is at rest is fitted with a circumferential groove *m* to allow the circulation of the pressure fluid

around the valve-stem when the motor is in its closed position. Communicating with the outlet-channel *k* is the outlet-port *d'*, to which is connected the pipe leading to the pressure-operated valve.

Between the outer end of the motor-valve *g* and the inner end of the removable plug *c* is an accumulating-chamber *p*, and formed through the motor is a diminutive passage *r'*, one end of which communicates with the chamber *b* and the other end with the inlet-channel *d* when the motor is at rest. Entering the head of the motor is an adjustable screw *m'*, the inner end of which is opposed to the diminutive passage *r'* to regulate the volume of the pressure fluid passing therethrough, it being necessary to restrict the flow of the pressure fluid through the passage *r'* to a lesser volume than through the passage *q* in order to insure the proper action of the valve.

Formed through the valve-body is the accumulating-chamber exhaust-port *q*, one end of which communicates with the chamber *b* and the other end discharges from the valve-body, and pivoted to the valve-body *a* contiguous to the outer end of the accumulating-chamber exhaust-port *q* is a valve *r* to close the same.

Connected to the valve-body is one end of a substantially U-shaped thermostatic blade *s*, the outer end of which is opposed to the pivoted valve *r*, and passing through the free end of the thermostatic blade *s* is an adjustable screw *t* to regulate the movement of the pivoted valve.

The valve-body *a* is fitted with an operating-fluid chest *u* contiguous to the inlet-port *d*, and connected to the chest *u* is one section, *v'*, of the operating-fluid pipe, the chest *u* being fitted with a throttle-valve *w* to cut off the flow of the operating fluid through the valve-body when so desired. Connected to the outlet-port *d'* is the other section, *v*, of the operating-fluid pipe leading to the pressure-operated valve *o*. The valve *o* consists of a valve-body *x*, having a plunger-valve *y* opposed to the pipe *z* for the heating agent. Fitted to the top of the valve-body is a diaphragm *a''*. The section *v* of the pressure-fluid pipe discharges directly upon the diaphragm *a''* to force it and the plunger-valve toward the heating-agent pipe, causing the valve *y* to close the same.

The operation of the invention is as follows: The reservoir *c'* is charged with operating fluid at a comparatively high pressure, and this operating fluid when the passage is not interrupted by the thermostatic valve passes from the reservoir to the pressure-operated valve. Assuming that it is desired to maintain the temperature of a room at 70° Fahrenheit, the adjustable screw *t* is set to hold the pivoted valve *r* closed against the open end of the diminutive passage *q* while the temperature remains at that degree or lower. The pressure fluid enters the ther-

mostatic valve through the inlet-port *d* and circulating around the valve-stem *i* passes in a small volume through the passage *r'* to the accumulating-chamber *p* and being unable to escape through the passage *q* accumulates therein and provides a sufficient pressure against the head of the motor to hold it firmly in its closed position, shutting off the communication between the inlet or outlet ports and retaining the motor on its seat regardless of the fluid-pressure against the valve-stems. When the temperature rises above the normal degree, the thermostatic blade *s* expands and relieves the pivoted valve *r* of the pressure of the adjustable screw *t*, allowing the valve to be opened by and permit of the escape of the operating fluid from the accumulating-chamber *p* through the passage *q*. When the head of the motor is relieved of the fluid-pressure, the operating fluid entering the motor-chamber through the inlet-port *d* moves the motor-valve longitudinally in the motor-chamber, bringing it into the position shown in Figs. 3 and 4, the motor being between the channel *e* and outer edge of the motor-chamber. When the motor is in this position, the operating fluid passes from the inlet-port through the motor-chamber to the channel *e* and then into the outlet-channel *k*, from which it escapes through the outlet-port *d'* and entering the pipe *v* passes to the pressure-operated valve *o*, applying sufficient pressure to the diaphragm *a''* to force it toward the pipe *z* and cause the valve to cut off the flow of the heating agent from the pipe *z* to the radiator. At this time the inner end of the passage *r'* is opposed to the channel *e* and a very small volume of the operating fluid passes through the passage to the chamber *p* and escapes from the chamber *p* through the passage *q*. When the temperature has again fallen to the normal degree, the thermostatic blade *s* contracts, bringing the adjustable screw *t* into engagement with the pivoted valve *r*, causing the valve to close the passage *q*, and the operating fluid having no egress through the passage *q* again fills the accumulating-chamber *p* and applies sufficient pressure to the head of the motor to cause it to return to its normal or closed position, as shown in Fig. 5 of the drawings, holding the motor firmly on its seat regardless of the fluid-pressure against the valve-stem. The flow of the operating fluid from the inlet to the outlet ports is now interrupted and continues so until the temperature of the room has again risen above the normal degree, when the above-described movement of the valve is repeated. To effect the opening of the pressure-operated valve, it is necessary to relieve it of the pressure of the operating fluid remaining in the outlet-channel after the motor has returned to its normal position, and this relief is accomplished by fitting the outlet-channel *k* with an escape-port *l*, the pressure fluid escaping from the pressure-operated valve *o* through the pipe *v* to the

channel *k* and circulating around the circumferential channel *m* in the valve - stem escapes through the port *l*. When steam is used as the operating fluid, this opening can 5 be employed for the drainage of the condensation. When the diaphragm has been relieved of the pressure of the operating fluid, the heating agent opens the plunger-valve and continues its circulation through the radiator or other heat-distributing appliance 10 until again checked by the action of the regulating-valve.

It is possible to set the apparatus to operate at any predetermined degree of temperature, and it is also possible to operate the 15 thermostatic valve either by steam or other fluid-pressure and to use the apparatus in conjunction with heating appliances operated either by steam or hot water.

20 I claim—

1. In a regulating-valve, the combination of a casing having a motor-chamber in the upper portion thereof, inlet and outlet channels leading to the motor-chamber, a motor-valve 25 located in the motor-chamber controlling the inlet and outlet channels and having a duct in communication with the inlet-channel, an accumulating-chamber supplied by the duct at the upper end of the motor-chamber, an 30 outlet - duct for the accumulating - chamber leading from the upper end of the accumulating-chamber to the outside, and a valve for controlling the outlet-duct.

2. In a regulating-valve, the combination 35 of a casing having a motor-chamber in the upper portion thereof, inlet and outlet channels leading to the motor-chamber, a motor-valve located in the motor-chamber controlling the inlet and outlet channels and having 40 a duct in communication with the inlet-channel, an accumulating - chamber supplied by the duct at the upper end of the motor-chamber, an outlet - duct for the accumulating - chamber leading from the upper end of the 45 accumulating-chamber to the outside, a valve for controlling the outlet-duct, and a thermostatically-operated valve to control the outlet-duct.

3. In a regulating-valve, the combination 50 of a casing, having a motor-chamber therein, inlet and outlet channels communicating with the motor-chamber, an outlet-duct leading from the motor-chamber to the outside of the casing; a supplemental outlet-channel leading 55 from the main outlet-channel to the outside of the casing, a motor-valve movable in the motor-chamber, having a duct communicating with the inlet-channel and outlet-duct, said motor-valve controlling the communication 60 between the inlet and outlet channels and the passage through the supplemental outlet-channel, a pivoted valve to control the outlet-duct, and means to control the valve by contraction and expansion, substantially 65 as specified.

4. In a regulating-valve, the combination 70 of a casing, having a motor-chamber therein,

inlet and outlet channels communicating with the motor-chamber, an outlet-duct leading from the motor-chamber to the outside 70 of the casing, a supplemental outlet-channel leading from the main outlet-channel to the outside, a motor-valve movable in the motor-chamber controlling the communication between the inlet and outlet channels and the 75 passage through the supplemental outlet-channel and having a duct communicating with the inlet-channel and outlet-duct, a pivoted valve to control the outlet-duct; a **U**-shaped thermostat having one end connected 80 to the casing and the other free and means carried by the free end of the thermostat to control the pivoted valve, substantially as specified.

5. In a heat-regulating valve, the combination 85 of a casing, having a central channel therethrough of varying diameters, an inlet-channel leading to the motor - chamber, an outlet-channel leading from the motor-chamber on the opposite side from the inlet-channel, an outlet-duct leading from the motor-chamber to the outside of the casing; and an 90 exhaust - channel leading from the outlet-channel to the outside; a motor-valve movable in the motor-chamber and having its 95 stem movable in the exhaust-channel, said motor-valve controlling the inlet and outlet channels and its stem the exhaust-channel; a pivoted valve to control the outlet-duct; a **U**-shaped thermostat having one end secured 100 to the casing and the other free, and a set-screw carried by the free end of the thermostat to adjustably control the pivoted valve, substantially as specified.

6. In a heat-regulating valve, the combination 105 of a casing, having a central channel therethrough and forming a motor-chamber, an inlet-channel leading to the motor-chamber, an outlet-channel leading from the motor-chamber on the opposite side from the inlet-channel, an outlet-duct leading from the motor-chamber to the outside of the casing; an exhaust-channel leading from the outlet-channel to the outside, a motor-valve movable in the motor-chamber and having its stem 110 115 movable in the exhaust-channel; said motor-valve controlling the inlet and outlet channels and its stem the exhaust-channel, and having a duct communicating with the inlet-channel and outlet-duct, a pivoted valve to 120 control the outlet-duct and means to control the pivoted valve as said means contracts and expands, substantially as specified.

7. In a regulating-valve, the combination 125 of a casing, provided with a central chamber therethrough, of varying diameters forming a motor-chamber, an inlet-channel leading to the motor-chamber, an outlet-channel leading from the motor-chamber on the opposite side from the inlet-channel, an outlet-duct leading 130 from the motor-chamber to the outside of the casing, and an exhaust-channel leading from the outlet-channel to the outside, a motor-valve movable in the motor-chamber, hav-

ing a duct communicating with the inlet-channel and outlet-duct, and having its stem movable in the exhaust-channel, said motor-valve controlling the inlet and outlet channels and its stem the exhaust-channel; a pivoted valve to control the outlet-duct, a U-shaped thermostat having one end connected to the casing and the other free, and means carried by the free end of the thermostat to 5 adjustably control the valve by the expansion and contraction of the thermostat, substantially as specified.

8. In a regulating-valve, the combination of a casing, provided with a central channel therethrough, of varying diameters, forming a motor-chamber, an inlet-channel leading to the motor-chamber, an outlet-channel leading from the motor-chamber on the opposite side from the inlet-channel, an outlet-duct leading 15 20

the casing; an exhaust-channel leading from the outlet-channel to the outside, a motor-valve movable in the motor-chamber and having its stem movable in the exhaust-channel, said motor-valve controlling the inlet and outlet channels and its stem the exhaust-channel, and having a duct communicating with the inlet-channel and outlet-duct, a pivoted valve to control the outlet-duct; a U-shaped thermostat having one end secured to the casing and the other free, and a set-screw carried by the free end of the thermostat, to adjustably control the pivoted valve, substantially as specified.

Toronto, April 3, 1901.
